ABSTRACT OF THE DISCLOSURE

A pump for feeding several heating circuits from a single boiler includes a single casing connected with the boiler and driving rotors located within the casing, each rotor being driven independently and being connected by a separate pipe joint with the inlet of a separate heating circuit.

This invention relates to a rotary pump for a heating fluid and refers more particularly to a double pump of this type which is particularly suitable for feeding separate heating circuits from a common boiler.

In many heating installations, for example, those of one family homes, the heating requirements of the individual rooms greatly differ one from the other due to their different locations with respect to reception of heat from the sun and also due to the different extent of use of the various rooms; economically it is most impractical to employ a single heating circuit for these different heat requirements. Therefore, in order to improve the efficiency of the heat installation as a whole, a single boiler has been provided with several separate heating circuits.

In prior art installations of this type wherein several separate circuits are used, so-called stage valves are built into each circuit; these valves are operated manually or thermostatically depending upon heat requirements of the room or rooms heated by the individual circuits. These valves must be operated by electromotors or electromagnets, so that their construction is complicated and expensive. Thus the costs of the installation as a whole are substantially increased, particularly since these valves must be added to all other regulating and circulating devices. Furthermore, they often cause operational failures of the installation.

An object of the present invention is to eliminate the use of these stage valves and to replace them by more reliable and less expensive means.

Other objects of the present invention will become apparent in the course of the following specification.

In the accomplishment of the objectives of the present invention it was found desirable to provide a rotary pump for supplying several separate heating circuits from a common boiler, wherein a common pump casing contains separate rotors or groups of rotors with independent drives, which are joined at the suction side to a common suction connection and which at the pressure side are provided with several pressure-transmitting connections for the separate heating circuits.

A pump of this type, as compared to the use of separate pumps for each heating circuit, has firstly the advantage of being less expensive due to its simpler construction; furthermore, by providing a common connection at the suction side the use of one shut-off device is eliminated, since in case of separate pumps two shut-off devices must be provided for each individual pump. The installation costs of a double pump are also smaller as compared to those required for two pumps. Another important advantage consists in that the larger mass of a double pump dampens particularly effectively the electromagnetic oscillations of the driving motor, which are unavoidable and

2

which are transmitted by tubular conduits connected to the pump as so-called body resonance.

In a final structural embodiment of the present invention, the double pump is provided in each of the two pressure connections with a flap functioning as forerunner 5 brake and as a check valve; the two pressure connections are also joined by a shut-off device which is located between them. A construction of this type makes it possible to maintain a satisfactory supply to both heating circuits even in the case of a breakdown of one pump unit, since then the shut-off device is opened and the still operating pump unit can be set to a correspondingly greater output by regulating means which will be described hereinafter.

According to a further embodiment of the invention 15 the pump can be provided with an additional connection to the return flow conduit of the boiler, said connection being associated by regulating devices with the pressure sides of the various rotors or rotor groups. Furthermore, a common pipe joint for the return flow of the heating water from the various heating circuits can be mounted in the pump casing and can be connected to the pipe joint providing the return flow of water into the boiler. According to this construction the water flowing back after the heating does not reach the boiler immediately, so that it can not cause corrosion therein, which can happen if the water is cooled to a great extent; on the contrary, this cooled water is mixed within the pump with warm water by the regulating means, so that there can never be a drop below the dew point at the inlet to the boiler.

It was found advantageous to provide the regulating 30 means in their closing position with an open minimal cross sectional area for the flow between the pressure sides of the rotors or rotor groups and the pipe joint for the return flow conduit to the boiler. Then the cold return water is always mixed with some hot water and this mixing can not be prevented by an erroneous closing of the regulating means. The regulating means are preferably constructed as automatic devices operating dependent upon conditions of the heating medium and air, or the outer temperatures. According to a preferred embodiment 35 of the invention a valve is arranged between conduits providing the return flow of the heating medium and the outflow of the heating medium from the boiler, said valve being preferably operated by means of a thermostat depending upon outer temperature conditions. This valve mixes cold return flow water with the hot water leaving the boiler. Such mixing was found to be particularly useful during transitory periods when the boiler is primarily used for preparing the water to be used for the heating.

The invention will appear more clearly from the following detailed description when taken in connection with the accompanying drawings showing by way of example only, preferred embodiments of the inventive idea.

In the drawings:

FIGURE 1 is a diagram illustrating the location of a 55 pump of the present invention in a heating installation.

FIGURE 2 is a diagram showing a somewhat different 60 pump in a heating installation.

FIGURE 3 is a section through a double heating pump 65 of the present invention.

FIGURE 4 is a similar section through a somewhat differently constructed pump.

Similar parts are designated by the same numerals or 70 letters in the various figures.

FIG. 1 shows a double pump 11 having a suction side which is supplied with a heating fluid, such as hot water, from a boiler 10 through a forerunner conduit KV. The pressure zone of the pump has two conduits which are connected with two separate circuits HV_I and HV_{II} for heating fluid. These two conduits are interconnected by a pipe connection having a shut-off device 13 which is located between them and behind forerunner brakes 12

which are located in the two conduits at their junction with the pump casing. The purpose of these brakes is to stop all forceful circulation when the pump is switched off; they also serve as relief valves and if one pumping unit gets out of order, they prevent a return flow through that pumping unit, so that after the shut-off device 13 is opened, the two heating circuits can be supplied, if necessary, from a single pumping unit.

The ends of the heating circuits HR_I and HR_{II} are connected to a conduit KR returning the fluid to the boiler 10.

In the construction of FIG. 2 the pump of the present invention is provided with two additional pipe joints KR and HR leading to the bottom of the boiler 10 and to the ends of the heating circuits, respectively. Furthermore, in accordance with this construction the conduit KV is connected with the conduit HR for the return flow through a valve 14 which is actuated by a thermostat 15.

FIGS. 3 and 4 show diagrammatically actual constructions of the double pumps. The pump of FIG. 3 has two pressure zones or chambers 21 which may communicate with a central collecting space through regulating valves 19. The valves 19 have an open cross-sectional area in the closed portion, so that they cannot completely shut off flow. They may be operated automatically by means (not shown) depending upon conditions of the heating medium, air or outer temperature. There are two rotors 16 driven by motor shafts 17 extending through projecting portions 18 of the casing. Separate drives are provided for the rotors and these drives may be operated from separate room thermostats (not shown). Each of the rotors actuates a separate circuit for the circulation of the heating medium, as indicated by the indicia HV_I and HV_{II} . Forerunner brakes 12 are located in these circuits; they consist of spring-engaged relief flaps or valves. The relief flaps 12 are pressed by their springs in the direction opposed to the flow of the heating medium through the respective pressure zones.

The construction of the pump shown in FIG. 4 is substantially the same as that of FIG. 3. However, FIG. 4 shows a collecting chamber 20 receiving the conduit HR of the heating circuits and the conduit KR for the boiler return flow. The arrangement indicated in FIG. 4 is that the openings of these conduits which lead into the collecting chamber 20, are angularly shifted relatively to each other, one opening being located in front of the plane of FIG. 4, while the other opening is located behind the plane of FIG. 4. They may be shifted to the extent of 90° relatively to each other.

Operation

Liquid rising from the boiler 10 reaches the pump through the inlet KV and enters into the suction zone of the pump. Rotors 16 transmit the heating liquid into the circuits the inlets of which are designated as HV_I and HV_{II} . The flow of the liquid within the pump is designated by arrows. According to the embodiment of FIG. 4 liquid returning from the heating circuits flows through the conduit HR back into the collecting chamber 20 and leaves the pump casing through the conduit KR , returning to the bottom of the boiler. The collecting chamber 20 also receives warm water from the pressure section of the pump, so that inflowing warm water is mixed with the outflowing cooled water. Regulating valves 19 are used to regulate the amount of the hot water which is to be admixed to the cooled water. In the constructions of FIGS. 3 and 4 the left-hand regulating valve is shown as being completely open, while the right-hand valve is shown as being closed.

It is apparent that the above-described examples have been given solely by way of illustration and not by way

of limitation and that they are subject to many variations and modifications within the scope of the present invention. All such variations and modifications are to be included within the scope of the present invention.

What is claimed is:

1. In combination with a single boiler and a plurality of separate heating circuits, a single pump casing, a plurality of pumping rotors in said casing, the number of said rotors being equal to that of said heating circuits, a separate drive for each of said rotors, the interior of said casing having a suction zone common to all rotors, a pipe joint connecting said suction zone with said boiler, said rotors forming separate pressure zones within said casing, separate pipe joints connecting each pressure zone with the inlet of a separate heating circuit, a separate relief flap in each pressure zone, a spring pressing said flap in the direction opposed to the flow of the heating medium through that pressure zone, a pipe connection interconnecting the pressure zones behind said flaps in relation to the direction of flow and means shutting off said pipe connection.

2. In combination with a single boiler and a plurality of separate heating circuits, a single pump casing, a plurality of pumping rotors in said casing, the number of said rotors being equal to that of said heating circuits, a separate drive for each of said rotors, the interior of said casing having a suction zone common to all rotors, a pipe joint connecting said suction zone with said boiler, said rotors forming separate pressure zones within said casing, separate pipe joints connecting each pressure zone with the inlet of a separate heating circuit, means connecting said pump casing with outlets of said heating circuits, a valve connected with the first-mentioned pipe joint and said means, and a thermostat operating said valve.

3. In combination with a single boiler and a plurality of separate heating circuits, a single pump casing, a plurality of pumping rotors in said casing, the number of said rotors being equal to that of said heating circuits, a separate drive for each of said rotors, the interior of said casing having a suction zone common to all rotors, a pipe joint connecting said suction zone with said boiler, said rotors forming separate pressure zones within said casing, separate pipe joints connecting each pressure zone with the inlet of a separate heating circuit, means connecting said pump casing with outlets of said heating circuits, means connecting said pump casing with the bottom of said boiler, said pump casing having a collecting chamber communicating with both said means, and regulating valves located between collecting chamber and said pressure zones.

4. A pump in accordance with claim 3, wherein said regulating valves have an open cross-sectional area in the closed position.
